CLAIM

The ornamental design for a gel ice hat, as shown and described.

DESCRIPTION

FIG. 1 is a front-perspective view of a gel ice hat, showing my new design;

FIG. 2 is a rear perspective view thereof;

FIG. 3 is a front elevational view thereof;

FIG. 4 is a rear elevational view thereof;

FIG. 5 is a left side elevation view thereof, the right side elevation view being a mirror image of FIG. 5;

FIG. 6 is a top plan view thereof;

FIG. 7 is a bottom plan view thereof;

FIG. 8 is a front perspective view in an alternate position of use with the outer band lifted from the inner band; and,

FIG. 9 is a rear perspective view thereof.

1 Claim, 7 Drawing Sheets
